[57] CLAIM

The ornamental design for a television monitor combined with video tape recorder, as shown and described.

DESCRIPTION

FIG. 1 is a perspective view of a first embodiment of a television monitor combined with a video tape recorder showing my new design;

FIG. 2 is a top plan view thereof;

FIG. 3 is a front elevational view thereof;

FIG. 4 is a rear elevational view thereof;

FIG. 5 is a left side elevational view thereof;

FIG. 6 is a right side elevational view thereof; and,

FIG. 7 is a perspective view thereof, with the lid portion in the open position.

FIG. 8 is a perspective view of a second embodiment of a television monitor combined with a video tape recorder;

FIG. 9 is a top plan view thereof;

FIG. 10 is a bottom plan view thereof;

FIG. 11 is a front elevational view thereof;

FIG. 12 is a rear elevational view thereof;

FIG. 13 is a left side elevational view thereof;

FIG. 14 is a right side elevational view thereof; and,

FIG. 15 is a perspective view thereof, with the lid portion in the open position.
